Specification for Design.

Patented July 6, 1920.

Application filed November 6, 1919. Serial No. 336,219. Term of patent 14 years.

To all whom it may concern:

Be it known that I, ADDISON B. CARLL, a citizen of the United States, residing at New York, in the county of New York and State of New York, have invented a new, original, and ornamental Design for Wrenches, of which the following is a specification.

Referring to the drawings:—

Figure 1 is a side elevation of a wrench, showing my new design;

Fig. 2 is a rear elevation of the same; and

Fig. 3 is a transverse section on the line 3—3, Fig. 1.

I claim:

The ornamental design for a wrench, substantially as shown.

In testimony that I claim the foregoing as my own, I have hereto affixed my signature in the presence of two witnesses.

ADDISON B. CARLL.
